(57) **CLAIM**

The ornamental design for a location receiver for radio frequency tracking system, as shown and described.

DESCRIPTION

FIG. 1 is a front elevational view of a location receiver for radio frequency tracking system showing my new design; FIG. 2 is a rear elevational view thereof; FIG. 3 is a side view, taken from the left side of FIG. 1; FIG. 4 is a side view, taken from the right side of FIG. 1; FIG. 5 is a top plan view thereof; and, FIG. 6 is a bottom plan view thereof.

The broken line showing is for illustrative purposes only and forms no part of the claimed design.
